W. B. CAROLUS.

BOLT AND NUT CUTTER

APPLICATION FILED OCT. 30, 1918

1,296,265.

Patented Mar. 4, 1919.

UNITED STATES PATENT OFFICE.

WILLIAM B. CAROLUS, OF STERLING, ILLINOIS.

BOLT AND NUT CUTTER.

1,296,265.

Specification of Letters Patent.

Patented Mar. 4, 1919.

Application filed October 30, 1918. Serial No. 260,246.

To all whom it may concern:

Be it known that I, WILLIAM B. CAROLUS, a citizen of the United States, residing at Sterling, in the county of Whiteside and State of Illinois, have invented a new and useful Improvement in Bolt and Nut Cutters, of which the following is a specification.

This invention relates particularly to bolt clippers, or combination bolt clippers and nut splitters.

The primary object of the invention is to provide an improved implement of the character described, having improved adjusting means to insure proper closing of the blades.

Further objects are to provide a simple, staunch and durable construction having improved means for adjusting the blades, and to provide improved hand-levers, of simple and cheap construction.

The invention is illustrated, in its preferred embodiment, in the accompanying drawing, in which—

Figure 1 represents a broken plan view of the improved device; Fig. 2, a side elevational view of the same; Fig. 3, an enlarged sectional view, taken as indicated at line 3 of Fig. 1; Fig. 4, a perspective view of one of the adjusting devices employed in connection with a hand-lever fulcrum of the device; Fig. 5, a perspective view, showing a guide bolt which moves in longitudinal slots in the plates, constituting the frame of the head of the implement and which serves also as an interlocking connection between a pair of adjusting screws of the form shown in Fig. 4; and Fig. 6, a perspective view of one of the adjustable lever-fulcrums.

In the preferred embodiment, which is illustrated, A, A represent a pair of swinging blades, joined by pivots 1 to connecting plates 2, constituting a frame for the head of the implement; B, B, a pair of hand-levers having their short arms connected by pivots 3 to the long arms of the blades A; and C, C, a pair of adjustable fulcrums for the hand-levers B, each of the fulcrums C having an adjusting device C¹ capable of moving longitudinally in guide slots with which the plates 2 are provided.

In the illustration given, the blades A are provided with longitudinal cutting edges 4 and with blade portions 4^a affording cutting edges 4^b which are perpendicular to the cutting edges 4. The blades may be used for clipping bolts, or for splitting nuts, as desired.

The plates 2 may comprise heavy sheet-metal plates which are stamped to suitable form to embrace the blades A, the plates having outwardly offset rearward extensions 2^a which serve to house the inner ends of the hand-levers and connecting parts. The offset portions 2^a of the plates are provided with longitudinal guide slots 5 in which are received the head-portions of fulcrum-adjusting stems of the character shown in Fig. 4.

Each of the hand-levers B, preferably comprises a wooden handle 6 and a pair of heavy metal plates, or stampings, 6^a. The plates 6^a are provided with complementary semi-tubular shank portions 6^b adapted to receive the handle 6, and are provided further with flat portions 6^c which afford between them a laterally open slot 6^d. The extremities of the flat portions 6^c embrace the rear ends of the long arms of the blades A and are connected therewith by means of the pins 3, the ends of which pins are housed by the offset portions 2^a of the plates 2. The concavo-convex shank portions 6^b of the handle-attaching plate 6^a are connected with the wooden handle 6 by means of rivets 7. It is preferred to equip one of the hand-levers with a rubber buffer 8, which is attached by means of a pin 9 which is capable of sliding freely through a perforation in the hand-lever. This is not essential, however.

Each of the fulcrums C, in the illustration given, comprises a short heavy pin which is provided with a transverse threaded perforation 10, adapted to receive the threaded portion of the adjusting device shown in Fig. 4. The end portions of the fulcrum C are journaled in the flat portions 6^c of the lever-attaching plates 6^a, and the end surfaces of the fulcrum C are housed, or partially housed, adjacent the inner surfaces of the offset portions 2^a of the plates 2.

Each adjusting device C¹ preferably comprises a threaded stem 11, which is adapted to screw into the threaded perforation 10 of the fulcrum C, and a head portion 11^a, which is adapted to move in the longitudinal guide slots 5 of the plates 2. It will be understood that the head portions 11^a of the two adjusting screws abut against each other and occupy the guide slots 5. The adjacent surfaces of the head portions 11^a are provided with recesses 11^b which cross each other in the manner shown in Fig. 4. The

recesses in the heads of the two adjusting screws are complementary and adapted to receive a guide bolt 12, which is fitted with washers 12^a and a nut 12^b. The guide bolt 12^a extends through a pair of the complementary recesses 11^b in the heads of the adjusting screws and through the slots 5 of the offset portions 2^a of plates 2, the washers embracing the outer surfaces of the plates, 5 as will be understood. The bolt 12 serves as a guide bolt and connection between the rear portions of the plates 2 and also as a means for locking the adjusting screws in adjusted position. It will be understood 10 that inasmuch as the heads of the adjusting screws are confined in the slots 5, turning the adjusting screws in the threaded sockets 10 of the fulcrum C will adjust the fulcrums toward or away from the longitudinal center line of the implement, thus enabling the blades A to be adjusted so that the cutting edges will meet properly. Either one of the recesses 11^b, may serve to receive the connecting bolt 12, depending 20 upon the recesses which is most available when the fulcrum is adjusted to the desired position.

The adjusting devices here illustrated and described render unnecessary the use of exterior adjusting devices, such as are commonly employed for connecting the handle portions of bolt clippers to the base or connecting portions which are pivotally connected with the blades. Moreover, this adjustment is independent of the use of any buffer or stop between the hand-levers. 30

The hand-levers described are of the improved character and of cheapened construction. The hand-levers may be made 40 adequately strong at a very low manufacturing cost. The saving in the use of metal is material, and the construction provides for the use of wooden handles. This is especially desirable where the device may be 45 used for cutting electrically charged wires, since the wooden handles themselves afford a fair degree of insulation, and the insulating effect may be increased, if desired, by wrapping or jacketing the handles with 50 additional insulating material.

The foregoing detailed description has been given for clearness of understanding only, and no unnecessary limitations should be understood therefrom, but the appended 55 claims should be construed as broadly as permissible, in view of the prior art.

What I regard as new and desire to secure by Letters Patent, is:—

1. An implement of the character set 60 forth, comprising a pair of pivotally-supported blades, hand-levers pivotally connected with said blades, a pair of spaced fulcrums for said hand-levers, and adjusting stems interposed between and connecting said fulcrums.

2. An implement of the character set forth, comprising a pair of pivotally supported blades, hand-levers pivotally connected with said blades, adjustable fulcrums for said hand-levers, and fulcrum-adjusting means and guiding means therefor permitting shifting of the fulcrum-adjusting means longitudinally with relation to said blades. 70

3. An implement of the character set forth, comprising a pair of blades, a pair of plates embracing said blades and pivotally connected therewith, a pair of hand-levers pivotally connected with the long arms of said blades, floating fulcrums for said hand-levers, and lateral stems extending from said fulcrums and having connections with said plates. 75

4. An implement of the character set forth, comprising a pair of blades, a pair of plates embracing said blades and pivotally connected therewith, a pair of hand-levers pivotally connected with the long arms of said blades, floating fulcrums for said hand-levers, and the lateral stems extending from said fulcrums and having slideable connections with said plates. 80

5. An implement of the character set forth, comprising a pair of plates, a pair of blades interposed between said plates and pivotally connected therewith, a pair of hand-levers pivotally connected with the long arms of said blades, a pair of floating fulcrums for said hand-levers, adjusting stems connected with said fulcrums, and guide connections between said adjusting stems and said plates. 90

6. An implement of the character set forth, comprising a pair of plates provided at their rear portions with longitudinal slots, a pair of blades interposed between said plates and pivotally connected with the front portions thereof, a pair of hand-levers pivotally connected with the long arms of said blades, a pair of fulcrums for said hand-levers, and lateral stems extending from said fulcrums and having head portions received by said slots. 105

7. An implement of the character set forth, comprising a pair of plates provided at the rear portions with central longitudinal guide slots, a pair of blades interposed between said plates and pivotally connected with the front portions thereof, a pair of hand-levers pivotally connected with the long arms of the blades, a pair of floating fulcrums for said hand-levers provided with threaded transverse sockets, and a pair of adjusting screws received by said sockets and having head portions slidably confined in said guide slots. 115

8. An implement of the character set forth, comprising a pair of plates provided at the rear portions with central longitudinal guide slots, a pair of blades interposed 120

between said plates and pivotally connected with the front portions thereof, a pair of hand-levers pivotally connected with the long arms of said blades, a pair of floating fulcrums for said hand-levers, inwardly-extending adjusting-stems connected with said fulcrums, and guide connections between said adjusting stems and said guide slots.

9. An implement of the character set forth, comprising a pair of plates provided at their rear portions with longitudinal guide slots, a pair of blades pivotally connected with the front portions of said plates, a pair of hand-levers pivotally connected with the long arms of said blades, a pair of floating fulcrums for the hand-levers provided with threaded sockets, adjusting screws connected with said sockets and having head portions received by said guide slots, and a bolt extending through the head portions of said adjusting screws and moving said adjusting stems and said guide slots.

10. An implement of the character set forth, comprising a pair of plates provided at their rear portions with longitudinal guide slots, a pair of blades pivotally connected with the front portions of said plates, a pair of hand-levers pivotally connected with the long arms of said blades, a pair of floating fulcrums for the hand-levers provided with threaded sockets, adjusting screws connected with said sockets and having abutting head portions received by said guide slots, each of said head portions being provided with a plurality of bolt-receiving recesses, and a connecting bolt between said plates extending through said recesses and movable in said guide slots.

11. An implement of the character set forth, comprising a pair of pivotally mounted blades, and a pair of suitably fulcrumed

hand-levers pivotally connected with said blades, each hand-lever comprising a pair of complemental plates having flat pivotal and fulcrum portions and having complemental concavo-convex socket portions, and handles secured in said socket portions.

12. An implement of the character set forth, comprising a pair of plates, a pair of blades pivotally mounted therein, a pair of hand-levers pivotally connected with the long arms of said blades, each hand-lever comprising a handle portion and a pair of complemental plates provided with complemental socket portions for a handle and provided with flat pivotal and fulcrum portions, a fulcrum journaled in each pair of complemental plates, and guide connections between the fulcrums of said hand-levers and said first-named plates.

13. An implement of the character set forth, comprising a pair of main plates provided at their rear portions with longitudinal guide slots, a pair of blades pivotally connected with the other portion of said plates, a pair of hand-levers pivotally connected with the long arms of said blades, each hand-lever comprising a handle portion and a pair of complemental attaching plates provided with flat pivotal and fulcrum portions receiving the handle portions, a fulcrum journaled in each complemental pair of attaching plates, an adjusting screw connected with each fulcrum and disposed between the said complemental plates, said adjusting screws having head portions movable in said guide slots, and connecting means, between said plates and the head portions of said adjusting screws, movable in said guide slots.

WILLIAM B. CAROLUS.
